UNITED STATES PATENT OFFICE.

EDWIN E. SLICK, OF PITTSBURG, PENNSYLVANIA.

METHOD OF MAKING PRODUCER-GAS.

No. 921,173.

Specification of Letters Patent.

Patented May 11, 1909.

Application filed November 30, 1907. Serial No. 404,561.

To all whom it may concern:

Be it known that I, EDWIN E. SLICK, of Pittsburg, Allegheny county, Pennsylvania, have invented a new and useful Method of Producing Gas, of which the following is a full, clear, and exact description, reference being had to the accompanying drawings, forming part of this specification, in which—

Figure 1 is a sectional side elevation showing a producer arranged to carry out my process and connected to a heating furnace; Fig. 2 is a front elevation of the same; and Fig. 3 is a detail view of the adjustable feeding mechanism.

My invention relates to the making of producer gas and particularly relates to the manufacture of fuel gas used in heating and for similar purposes. In existing methods of making such gas from solid fuel, great difficulty has been had in preventing clinkering and caking of the fuel bed and in avoiding the formation of large holes or passages through the fuel bed permitting the undisturbed passage of the air through the producer and resulting in the uneven gasifying of the fuel and making of a lean gas having poor heating qualities.

The object of the invention is to provide a simple and effective process in which the above difficulties are avoided and are overcome and a rich gas having high heating value is easily and cheaply made.

The invention consists in maintaining a body of incandescent fuel in the producer and in regulating the fuel supply so as to spread the fresh fuel evenly over the top of the fuel bed.

The invention further consists in preventing the caking of the fuel and in avoiding the formation of channels or large openings through the fuel bed and in regulating the supply of air so as to gasify the fuel evenly over the surface of the bed and form a rich gas having a practically uniform heating value.

In the drawings, 2 represents the furnace chamber of the heating furnace, 3 the flat roof thereof supported upon transverse water pipes 4, and 5 is the producer chamber at the end opposite to that at which the billet or other metal pieces are fed in. This producer chamber may be of any desired shape and may be provided with either straight or sloping side walls. The chamber is free from any grate bars, supports or other projections which would interfere with the de-

scent of the charge. It is preferably provided at the bottom with an extension 6 forming a water seal through which the ashes may be raked out.

The coal is fed into the hopper 7 supported at one side of the producer and having below its throat a feed shelf 8 from which the descending fuel is forced into the producer by feed gates 9. These gates are preferably made in sections as shown in Fig. 3, each section being secured to the support 10 by adjustable screw stems 11 so as to adjust the amount of feed at any particular point in the width of the feed shelf. The bar 10 is reciprocated by any suitable connections, as by the bell crank 12 connected by rods 13 with the eccentrics on the driven shaft 14.

In order to introduce air, I preferably provide a blast box 15 having an outlet throat or port 16 leading through the side wall of the producer, or preferably through its lower end. Compressed air for this wind box is brought from the air main 17 through pipes 18 leading to opposite ends of the blast box. The blast box is divided into six chambers by baffle walls 19 therein and the inlet end of each of these chambers so formed is controlled by valves 20. The blast box is preferably provided with a depending flange 21 which enters the water seal to compel the air to enter and ascend through the charge.

22 are poke holes extending through the front of the producer. In the operation of the producer, the coal is pushed sidewise into the top portion of the charge and descends therein in the ordinary manner. There are, however, no grates or inside projections which retard or interfere with the free descent of the charge. This charge rests on the ash bed and descends as the ashes are raked out through the water seal. By pushing the charge in sidewise below the point of supply, the fuel is spread evenly over the bed and there are no holes burned through the top for easy passage of the air. The action in any portion may be varied by varying the draft in this portion and also by varying the stroke of the pusher in this portion. In practice, the pushers are preferably reciprocated continuously and serve to continuously force fresh fuel over the fuel bed, thus giving a uniform quality of gas.

The shape and form of the producer may be varied widely. It may be connected by pipes to the point of use instead of directly connected as shown. The air blast box may

be at any convenient level below the fuel feed and many other changes may be made without departing from my invention.

I claim:—

5 1. The method of making producer gas consisting in supplying coal to a producer, burning the coal in said producer, causing the coal to gradually descend by removing ashes from the bottom of the producer, continuously feeding portions of fresh coal across the top of the bed of burning coal, supplying air under pressure to the bottom of the fuel bed, and regulating the rate of feed for the coal and air across the width of

15 the coal bed; substantially as described.

2. The method of making producer gas, consisting in supplying solid fuel to a producer, burning said fuel in the producer causing the fuel to gradually descend in the producer, continuously feeding portions of fresh

fuel across the top of the fuel bed, supplying air to the bottom of the fuel bed and regulating the feed of the air across the width of the fuel bed; substantially as described.

3. The method of making producer gas, 25 consisting in supplying solid fuel to a producer, burning said fuel in the producer causing the fuel to gradually descend in the producer, continuously feeding portions of fresh fuel across the top of the fuel bed, supplying air to the bottom of the fuel bed, and regulating the rate of feed for the fuel and air across the width of the fuel bed; substantially as described.

In testimony whereof, I have hereunto set my hand.

EDWIN E. SLICK.
